FOOT MASSAGER

Walter Gustlin, Laguna Beach, Calif.

Application September 24, 1948, Serial No. 50,920

2 Claims. (Cl. 128—57)

1

This invention relates to improvements in devices for massaging and treating feet.

The massaging device of this invention is of simple construction. It is designed to be heated or cooled, and is preferably hollow with a wide-mouthed opening for the introduction of a heating or cooling medium. It may be heated electrically. Heating or cooling simultaneously with massaging relieves muscular foot aches caused by fatigue and the like.

The massager of this invention is generally cylindrical so that it may be rolled on the floor or other surface. It is formed with one, or preferably two tread surfaces, on which the soles of the feet are pressed as the massager is rolled on the floor. The tread surface or surfaces are formed with large irregularities which exercise the feet as the massager is rolled under them. There are many welts on the tread surfaces which perform a double function. They increase the area of the tread surfaces and, pressing into the skin, increase the area of skin contact, giving an increased rate of heat transfer between each tread surface and the sole of the foot brought into contact with it. These welts also prevent slippage between the tread surfaces and the soles of the feet as they are rolled over them.

The invention includes a preferred form of massager with two tread surfaces divisible at about the longitudinal center giving two massagers, each having suitable closing means. These may be used independently of each other.

The invention will be more fully described in connection with the accompanying drawings in which:

Fig. 1 is a side elevation showing a massager of preferred design;

Fig. 2 is an exploded view showing the side elevation of the various components of an alternative design of massager; and

Fig. 3 is an enlarged cross-sectional view taken on the line 3—3 of the massager shown in Fig. 1.

In the embodiment shown in Fig. 1, the elongate, hollow cylinder, molded preferably from glass, has an integral end wall 11. The opposite end of the cylinder is open. The annular flange 13 at the open end 12 is concentric with the axis of the cylinder. On the outside surface of flange 13, a thread 14 is molded to accommodate a similarly threaded, removable, water tight cap 15 which is screwed into place after a desired thermal medium such as chunks of ice or hot water is put into the massager.

The portions of the cylinder indicated by numbers 16, 17 and 18 are of larger diameter than the

2

rest of the massager and make contact with any flat surface on which the massager is rolled. As shown on the drawings, the rollers 16 and 18 are located at the ends of the cylinder and roller 17 is located substantially in the center. A milling 19 may be molded into the periphery of these rollers to provide better traction between the rollers and the flat surface, but such milling is optional.

10 Tread surfaces 20 and 21 are formed between these roller sections. Each is designed to accommodate a foot sole. A plurality of longitudinal ribs 22 are spaced around the tread surfaces 20 and 21 to provide the desired kneading action of 15 the soles of the feet. A design consisting of a series of slightly raised welts 23 arranged in a herringbone pattern is molded along each of the longitudinal ribs on the tread surfaces 20 and 21. The raised welts increase the rate of heat transfer 20 between the soles of the feet and the tread surfaces and the soles of the feet. Such means for increasing the traction is particularly desirable 25 on a massager made of a material which presents a slick surface, such as glass.

The interior surface 24 is substantially smooth and advantageously follows the contour of the exterior surface so as to provide a massager of maximum strength with minimum weight and uniform heat transfer.

The construction of the massager of Fig. 2 differs from the one shown in Fig. 1 in that the massager is molded in two units each containing one tread surface rather than two. Each of 35 the units 29 and 30 of the massager is a hollow cylindrical structure preferably molded from glass and substantially half as long as the massager shown in Fig. 1. Unit 30 has an integral end wall 31 and the opposite end 32 is open. 40 Roller surfaces 33 and 34 are provided at opposite ends of the tread surface. Milling 35 can be molded on the roller surfaces if desired. The contour of the tread surface 36 between the rollers is the same as that of tread surface 21 in Fig. 45 1. Longitudinal ribs 37 and welts 38 serve the same purpose as described above.

An annular flange 39, concentric with the axis of the cylinder is molded to the edge of the open end 32. Threads 40 are located around the outside of the flange 39 to accommodate a removable water-tight union 41. This union 41, fabricated from any suitable metal or plastic, is preferably cylindrical and is provided with water-tight bulk-head 42 which separates the two units 29 and 30. 50 Threads 43 are formed on either side of the bulk-

head 42 so that the union 41 may be screwed onto the flanges at the open ends of units 29 and 30. This gives a dual exerciser, the two halves of which may be heated to a different temperature. For instance, one may be hot and the other cold. The bulkhead is therefore preferably made of heat insulating material. Caps such as the cap 15 of Fig. 1 may be supplied so that each of the units 29 and 30 may be converted into a complete massager capable of being used independently of the other.

The massager may be made from glass, any suitable metal, or plastic having a high heat conductivity. Instead of ribs other irregularities may be provided to produce the desired massaging effect. The welts must be of relatively small area and may be of any suitable shape and number and may be arranged as desired.

What I claim is:

1. A foot massager formed of two hollow portions and a union at about the longitudinal center of the massager to which each is threaded, each hollow portion being open at the end united to the union, a bulkhead in the union to separate the respective hollow portions, a roller surface at each end of the massager of larger diameter than the rest of the massager capable of bearing simultaneously on a flat surface, each portion being provided with a tread surface, longitudinal ribs spaced radially around each tread surface to knead the sole of a foot brought into contact therewith, and on each rib a plurality of welts of such small size as to have no appreciable mas-

saging action on the sole of a foot brought into contact therewith but facilitating the transfer of heat between the tread surface and the sole of a foot in contact therewith and providing traction for the sole of a foot on the tread surface.

5 2. A rollable, hollow foot massager of cylindrical contour, comprising a tread surface having a plurality of longitudinal ribs, the surface of each rib being provided with two groups of small 10 parallel straight welts, the groups being arranged on the rib in herring-bone formation, each rib terminating short of the depressed area defining adjacent ribs, and an annular roller surface at each end and at the middle of the massager, said 15 roller surfaces being of larger diameter than the tread surface and capable of bearing simultaneously on a flat surface.
